UNITED STATES PATENT OFFICE

2,124,392

TRAFFIC-SIGNALING SYSTEM

Howard H. Bell, Schenectady, N. Y., assignor to
General Electric Company, a corporation of
New York

Application July 19, 1933, Serial No. 681,125

5 Claims. (Cl. 177—337)

My present invention relates to traffic signalling systems, and more particularly to systems in which continuously-operated intersection-signals and normally-inactive traffic-actuated signals are used to control traffic along a main highway.

The principal object of my invention is to provide an improved system of control wherein the traffic-actuated signals normally indicate the right of way to the main highway traffic and upon approach of vehicles on the cross streets will give the right of way to such vehicles only during a potential stop period on the main highway.

Another object of my invention is to provide a traffic-actuated intersection-signal which will operate to give the right of way to the cross street only during potential stop periods on the main highway in a system in which successive continuously-operated intersection-signals are timed in progression.

For a consideration of what I believe to be novel and my invention, attention is directed to the following specification, the accompanying drawing and the appended claims.

Fig. 1 of the drawing illustrates diagrammatically a system of traffic control embodying my invention; Fig. 2 is a diagrammatic illustration of the arrangement of the continuously-operated and traffic-actuated signals along a main highway, and Fig. 3 is a timing chart illustrating the arrangement of the green periods in a progressively-timed system and the relative arrangement of the synchronizing cams for carrying out my invention.

A set of continuously-operated intersection-signals is indicated at A and a set of normally inactive traffic-actuated signals is indicated at B. Each of the sets of signals comprises two series of three lamps each, one series for the main highway and one for the cross street. The lamps are marked "G", "A" and "R", respectively indicating green, amber and red, which are the signals used to indicate go, caution and stop. The number of signal lamps in a group may vary in accordance with city regulations and the requirements of each intersection. The three-lamp arrangement is, however, generally used.

The group of lights indicated as A are continuously operated in a predetermined sequence by a controller indicated at 3 which is driven by a motor 4. The controller 3 is connected to a source of current indicated by conductors 5 and 6 through conductors 7 and 8. The motor 4 comprises a stator 9 which is continuously energized

through conductors 10 and 11 connected to terminals on the controller 3, and a disk armature 12 which drives the controller 3 through a clutch 13 and a shaft 14. The clutch 13 is indicated as a normally closed disk clutch which may be opened by energizing a clutch magnet 15. The controller 3 may be any suitable controller for operating the signals in a predetermined sequence. I prefer to use, however, a controller such as is described in U. S. Patent No. 2,050,039, issued August 4, 1936, to Campbell and Byer and assigned to the same assignee as the present application. These controllers, briefly, comprise a multiple switch operable to energize in a predetermined sequence, the signal circuits for a group of traffic signals, and a timer for controlling the operation of the multiple switch and thereby controlling the relative lengths of the time periods for each signal within a sequence or cycle. The speed of the driving motor 4, which is connected through a connecting means, viz. the clutch 13 in the present arrangement, determines the length of a total cycle, and thereby the actual length of the signal periods within the cycle or sequence.

The continuously-operated signals are placed under the control of a master controller 16. This controller receives energy from lines 5 and 6 through conductors 17 and 18 and is driven by a motor 19 through a shaft 20. The motor comprises a stator 21 which is continuously energized through conductors 22 and 23, and a disk armature 24 which is connected to the shaft 20. For the purpose of controlling the operation of the signal controllers, a cam 25 provided with a projection 26 is mounted on shaft 20 and is arranged to rotate therewith at the rate of one revolution for each cycle of operation of the signals 1. The cam 25 is arranged to separate normally-engaging contacts 27 and 28 once during each revolution. This is accomplished by mounting the contact 28 on a contact spring 29, the end of which rides on the cam surface 25. The separation of the contacts takes place when the end of the spring 29 rides over the projection 26. Contact 27 is connected to line conductor 6 through conductor 30 and contact 28 is connected to a synchronizing conductor 32 through a conductor 31. Although I have shown a separate master controller it is to be understood that this controller may be one of the intersection controllers equipped with a cam 25 and the contacts 27 and 28 connected as above described.

The shaft 14 of the controller 3 is provided with a cam 33 corresponding to the cam 25. This

cam is arranged to rotate with the shaft at the rate of one revolution for every cycle of operation of the signals A. The cam 33 is provided with an indent 34 and is arranged to close normally-open contacts 35 and 36 once during each revolution. The contact 36 is mounted on a contact spring 37, the end of which rides on the cam surface 36 and causes an engagement, or closing, of the contacts 35 and 36 when it rides into the indent 34. The contact 35 is connected to the synchronizing conductor 32 by conductor 38 and the contact 36 is connected in series with clutch coil 15 and by conductor 39 to the line conductor 5.

15 In operation the contacts 27 and 28 of the master controller normally engage each other and therefore connect the synchronizing conductor 32 to line conductor 6, this circuit being from conductor 32 to conductor 31, contact spring 29, contacts 28 and 27, conductor 30 to line conductor 6. The contacts 35 and 36 of the continuously-operated controller are normally opened but are closed once during every cycle of operation of the intersection signals 1. At the instant that these contacts 35 and 36 engage each other a circuit is completed through the clutch coil 15. This circuit may be traced from line conductor 5, conductor 39, clutch coil 15, contact spring 37, contacts 36 and 35, conductor 38, synchronizing conductor 32, conductor 31, contact spring 29, contacts 28 and 27, conductor 30 and line conductor 6. The clutch coil 15 thereupon opens clutch 13 against the bias of a spring 40 and thereby disconnects the drive motor 4 from the shaft 14 and stops the operation of the controller 3 and the signals A. The master controller 16 in the meantime continues to operate and rotates the cam 25 so that the spring 29 rides onto the projection 26. At this instant the circuit through the clutch coil is broken by the separation of contacts 27 and 28 and the clutch 13 closes. The cam 33 thereby rotates and separates contacts 35 and 36 by the time the cam 25 is rotated far enough to allow the contacts 27 and 28 to again engage each other. The circuit through the clutch coil 15 therefore remains broken. Under normal conditions, that is, when the controller 3 is in synchronism with the master controller 16, the contacts 35 and 36 are closed at the instant that contacts 27 and 28 are opened, whereby the clutch coil 15 remains deenergized and the operation of the controller 3 is not interrupted.

55 In Fig. 2 I have indicated the automatically-operated signals A alternately arranged with the vehicle-actuated signals B at intersections along a main highway. This, of course, is only an arbitrary arrangement, since it is entirely possible that between automatically-operated intersections there will be more than one small street crossing over which few vehicles travel, and at which it is unnecessary to have a continuously-operated signal. It is also desirable, however, to restrict the crossing of vehicles at these intersections to such times as will not interfere with the progression of the stream of traffic along the main highway. Such times are necessarily the periods of times that would be allowed to this traffic if continuously-operated signals were used.

70 The timing of signals along any particular highway may be such that the cycles will be in unison and the green and stop periods will be of common duration, or they may be so arranged that the go periods will be offset with respect to each other in such a manner that a vehicle 75 traveling along the highway at a predetermined

speed will always have the right of way. This latter arrangement has become known as progressive timing of the signals. My invention is applicable to both arrangements of signals and is particularly useful in the progressive arrangement of the signals. 5

The traffic-actuated signals B are similar to the signals A comprising the two series of three lamps, each indicating respectively as "G", "A" and "R". Of these signals the "G" signal on 10 the main street and the "R" on the cross street are normally energized. The whole group of signals is controlled by a circuit controller 41, which is normally at rest. When a vehicle approaches on the cross street, however, it operates a treadle 15 and the controller is caused to operate the signals B through a cycle of operation and this cycle is properly timed in relation to the signaling cycles of the adjacent intersections on the highway as will be presently explained. To accomplish this operation the controller 41, which is a duplicate of the controller 3, is connected to lines 5 and 6 by conductors 42 and 43 and is arranged to be driven by a continuously-energized motor 44 comprising a stator 45 receiving energy 25 through conductors 46 and 47, and a disc armature 48. The disc armature is connected to the controller 41 through a clutch 50 and a shaft 51.

The clutch 50 in the traffic-actuated signals is normally open and the controller 41 is, therefore, 30 normally at a standstill. This is accomplished by providing on the shaft 51 a cam 52 having an indent 53 and a lug 54. A pair of contacts 55 and 56 are controlled by this cam. The contact 56 is mounted on a contact spring 57, the end of which rides on the cam surface 52. While the 35 spring rides on this cam surface the contacts 55 and 56 are separated, but when the spring 57 rides into the indent 53 the contacts engage each other. The contact 56 is connected in series with 40 clutch coil 58, and conductor 59 to line 5. The contact 55 is connected in series with a switch 60 through conductor 61. The switch 60 also controls the energization of the clutch coil 58 and is under the control of the cam 52 and traffic-actuated switches 62 and 63. These switches are located in the path of the vehicles approaching the intersection from either direction on the cross street. They may be closed by the weight of the vehicle or by any other suitable device or means 50 which detects the presence of a vehicle.

The switch 60 comprises two blades 64 and 65 which are maintained at an angle to each other in one or the other of two positions by a spring 66. In one position, that is, the position indicated by solid lines in the drawing, the switch blade 65 engages a contact 67 which is connected by a conductor 68 to line 6. In this position of the switch therefore a circuit is completed through the clutch coil 58 which may be traced 60 as follows: line 5, conductor 59, clutch coil 58, contact spring 57, contacts 56 and 55, conductor 61, switch blade 65, contact 67, conductor 68 and line 6. This is a complete circuit across the line conductors 5 and 6 and the coil 58 is energized, 65 thereby maintaining the clutch 50 in the open position.

When either switch 62 or 63 is closed by a vehicle passing over them, a circuit is closed from line 6 through conductor 70, switch 62 or 63, 70 conductor 71, coil 72 and conductor 73 to line 5. The coil 72 is thereby energized and pulls down its armature 74 against the pull of spring 75 and the hook 76 engages the switch blade 65 and pulls it down to the position indicated by dotted 75

lines into engagement with contact 77. The contact 77 is connected to the synchronizing conductor 32 by a conductor 78. In this position therefore the clutch coil 58 is in circuit with the synchronizing conductor 32 and remains energized until the master controller separates its contacts 27 and 28. The circuit in this case may be traced from line 5, conductor 59, coil 58, contact spring 57, contacts 56 and 55, conductor 61, switch blade 65, contact 77, conductors 78, 32 and 31, contact spring 29, contacts 28 and 27, conductor 30 and line 6. When the switch arm 65 is moved from contact 67 to contact 77, the circuit to the clutch coil 58 is momentarily broken. This momentary interruption is of such short duration, however, that the cam 52 does not move sufficiently to separate the contacts 56, and consequently, this change of connections is ineffective at this time to start the motor. In the drawing the contacts 67 and 77 are shown as widely separated. It is clear to those skilled in the art, however, that the drawing is merely diagrammatic, and that the two contacts being at the same potential may actually be brought sufficiently close to each other so that when the switch arm 65 passes from one to the other, it may at one point of its travel, touch both contacts, and thereby maintain the circuit to the coil 58 during the change of connections.

In operating a system of this type, the green periods of the successive intersections are adjusted with respect to each other, as indicated by the blocks 80, 81 and 82 in Fig. 3. In this figure I have represented a series of shaded rectangular blocks to represent the green periods of several consecutive intersections. As stated above, the master controller may be embodied in an intersection circuit controller. Block 80 therefore represents a green period at the master control intersection. Block 81 represents the green period at a continuously-operated intersection A. This block is slightly offset from the block 80 and the reference line R—R to indicate that this green period starts slightly later than the green period at the master intersection. The blocks 82 and 83 are similarly offset. The amount of offset is, of course, dependent upon the distances between the intersections and the speed at which it is desired that cars should travel along the highway. At an instant at which all the signals are green on the main highway, as indicated by a line x—x for example, the master cam 26 is arranged to break the circuit across the contacts 27—28. The cams 33 and 52, together with the cams corresponding thereto, are arranged to close their respective contacts 35—36 and 55—56 at the same instant. With this arrangement of the cams the clutch 58 will be energized and the controller 41 will remain at a standstill with a green main street indication if the switch 60 is in the position shown in full lines in Fig. 1. If the switch 60 is then moved by the treadle switches 62 or 63 and magnet 74 to the dotted line position shown in Fig. 1, the clutch coil 58 will become deenergized when the cams assume the position, shown in Fig. 3 at the next cycle of operation, and the cam 62 will begin to rotate counter-clockwise. The contact spring 57 will ride on the cam surface 52 and separate the contacts 55 and 56. The projection 54 will thereafter engage the blade 64 and move it upwards until the switch blade 65 is pulled upward into engagement with contact 67. This will then permit the cam 52 to make a complete revolution or until the spring 57 moves into the

indent 53. The contacts 55 and 56 then engage each other and complete the circuit through clutch coil 58 from line 5 to line 6. If the switch blade 65 has been pulled down into engagement with contact 77 by another actuation of treadle 62 or 63, the controller 41 will, of course, continue to operate in synchronism with the master controller, if not, the controller stops on the green main highway indication until the approach of a vehicle on the cross street has caused the switch 60 to be moved into engagement with contact 77.

The method of obtaining the adjustment of the cams is a relatively simple matter since, as pointed out above, all the controllers are alike. Each of the cams make one revolution per cycle and its relative position to the signal periods of its own controller can be adjusted. The adjustments for the master cam and for the intersection controller cams are determined from a chart which is made up for each set-up of the signals, that is desired. For a progressive arrangement the starting points of the green periods are indicated as being displaced with respect to each other a certain amount as, for example, indicated in Fig. 3. Since it is desired to maintain a green or "go" signal on the main highway at the normally-inactive intersection, a line x—x is chosen which intersects each one of the green periods to indicate at what point in the green periods of each controller the clutch circuit or synchronizing circuit is to be closed. For the master cam this circuit is, of course, opened at the corresponding instance. It is evident from Fig. 3 that the last intersection cam will have to be set to close the synchronizing circuit in illustrated example nearer to the beginning of the green period than the cam preceding and that the master cam will separate the contacts later than any of the others close their respective contacts. Assuming then that all controllers are set to start at the main street green indication and they are simultaneously started, the last controller will be stopped by the closing of its contacts and the energization of its clutch coil until the master cam opens its contacts as above explained. The intermediate controllers will, of course, line up correspondingly and they will all start up at the moment the master cam opens the synchronizing circuit. Since the cycles of operation are the same, the start of the green period of each controller will retain its relation to the start of the green periods of the other controllers as long as the synchronizing cams and circuit are used. If then the normally-inactive controllers are placed under the control of the synchronizing cam and circuit, by the vehicle-actuated switches, their respective signal periods will automatically assume the positions indicated by the Figure 3 and therefore will permit the crossing of the main highway without interfering with the progression of traffic on the main highway.

What I claim as new and desire to secure by Letters Patent of the United States, is:

1. In a traffic-signaling system, the combination of a plurality of groups of traffic signals, circuit controllers arranged to operate said groups of signals respectively, continuously-operating motors and connecting means for connecting said motors to drive said controllers respectively, a normally-inactive controller connected to one of said groups of signals, a continuously-operated motor for driving said controller, connecting means for effecting operation or stoppage of said

controller, a cam operated by said controller for controlling said last-mentioned means and for effecting a stoppage of said controller when said controller has operated its traffic signals to indicate the right of way to traffic on the main highway, means for controlling said connecting means for synchronizing the operation of said controllers, traffic actuated means and means responsive to said traffic actuated means for transferring control of said stopping and operating means to said synchronizing means for starting operation of said controller in a predetermined time relation with respect to said other controller for at least one operating cycle.

15. 2. In a traffic-signaling system, the combination of a plurality of groups of traffic signals, a plurality of circuit controllers arranged to operate said groups of signals in a predetermined cycle respectively, a motor and connecting means between said motor and controller, means for continuously operating said controllers, a master controller and a synchronizing circuit controlled thereby connected to each of said connecting means for maintaining said controllers in synchronism, a normally inactive controller and a group of signals operated thereby, a continuously-operating motor for driving said controller, means for disconnecting said motor from said controller when the signals operated thereby indicate the right of way to said main highway, a cam operated by said controller for controlling said last-mentioned means, traffic-actuated means, means responsive to said traffic actuated means for transferring control of said disconnecting means to said synchronizing circuit, and means operated by said master controller for delaying the operation of said connecting means so as to start said controller in proper time relation relatively to said continuously-operated controllers.

30. 3. In a traffic signaling system, the combination of a plurality of groups of signals arranged at intersections along a highway respectively, controllers connected to several of said groups of signals respectively and arranged when driven to operate said signals in a predetermined cycle and to operate corresponding signals in the several groups in a predetermined progressive relation, means for continuously driving said controllers, means for connecting said driving means to said controllers, controllers connected to others of said groups of signals arranged when driven to operate said signals through the same sequence as said first mentioned signals are operated, said last mentioned groups of signals being arranged to normally indicate the right of way to the main highway, means for driving said last mentioned controllers, means for connecting said last mentioned controllers to said last mentioned driving

means, vehicle actuated means responsive to an approaching vehicle on the cross street arranged to prepare said last mentioned connecting means respectively for connecting said controllers to said driving means, and synchronizing means for controlling all of said connecting means so as to synchronize the operation of all of said controllers, and thereby maintain the established relation between corresponding signals in the several groups of traffic signals.

4. In a traffic signaling system, a plurality of groups of traffic signals arranged at intersections of a main highway and cross streets respectively, controllers connected to several of said groups of signals and arranged when driven to operate said signals in a predetermined cycle respectively, continuously operating motors, clutch means normally connecting said motors to said controllers, controllers connected to the remaining groups of signals and arranged respectively when driven to operate said signals at the same sequence as said first-mentioned groups of signals are operated, clutch means between said last mentioned controllers and their respective motors, means for opening said last-mentioned clutches when the respective groups of signals indicate right of way to the main highway, vehicle actuated means responsive to an approach of vehicles at the respective last-mentioned intersections for preparing said last-mentioned clutches to close, and synchronizing means for closing all the clutches of the system at a common instant in each operating cycle.

5. In a traffic signaling system, the combination of a plurality of continuously operated groups of traffic signals, circuit controllers connected to said groups of signals, motors for driving said controllers and clutch means for connecting said motors to said controllers, a master controller and synchronizing circuit controlled thereby connected to control said clutch means for maintaining said controllers in synchronism, a normally-inactive controller, a continuously operating motor for driving said controller, clutch means for connecting and disconnecting said motor from said controller, a cam operated by said controller for controlling said clutch to disconnect said motor from said controller when the signals operated thereby indicate the right of way to traffic on the main highway, and traffic-actuated means for making said clutch responsive to said master controller and synchronizing circuit in response to actuation by a vehicle approaching on the cross street, whereby said last-mentioned controller operates for at least one cycle in synchronism with said first-mentioned controllers.

HOWARD H. BELL.
